HAND OPHTHALMOSCOPE

Charles Henry Keeler, Clewer Green, Windsor,
England

Application March 18, 1953, Serial No. 24,091

Claims priority, application Great Britain
September 19, 1952

Term of patent 14 years

(Cl. D57—7)

To all whom it may concern:

Be it known that I, Charles Henry Keeler, a subject of the Queen of Great Britain, Northern Ireland, and the Isle of Man, residing at Sefton Lawn, Clewer Green, Windsor, Buckinghamshire, England, have invented a new, original, and ornamental Design for a Hand Ophthalmoscope, of which the following is a specification, reference being had to the accompanying drawing, forming part thereof:

Fig. 1 is a front perspective view of a hand ophthalmoscope showing my new design;

Fig. 2 is a side perspective view thereof;
Fig. 3 is a rear elevational view; and
Fig. 4 is a top plan view.

I claim:
The ornamental design for a hand ophthalmoscope, as shown.

CHARLES HENRY KEELER.
